OVERHEAD TROLLEY DEVICE

Samuel S. Matthes, Mansfield, Ohio, assignor to
The Ohio Brass Company, Mansfield, Ohio, a
corporation of New Jersey

Application June 16, 1938, Serial No. 214,039

2 Claims. (Cl. 191—38)

My invention relates to improvements in overhead trolley systems adapted particularly for use in the operation of trolley buses.

One object of my invention is to provide at branch or turn-out points a construction which will be more adapted to the conditions required at branch and turn-out points than is usual in such systems. Other objects will be disclosed as the description of my invention proceeds.

10 My invention resides in the new and novel construction, combination and relation of the parts herein described and shown in the accompanying drawing.

15 In the drawing—

Fig. 1 is a schematic view of my invention looking down upon the same.

Fig. 2 is a side view of an enlarged portion of my invention as later described.

Fig. 3 is a top view of Fig. 2.

20 Fig. 4 is an enlarged view of another portion of my invention as later described.

Fig. 5 is a top view of Fig. 4.

25 In the operation of trolley buses there are two trolley wires of opposite polarity which are employed, and it is necessary to keep these two polarities separated electrically and mechanically and at branch or turn-out points, this has been a considerable problem as it is necessary to maintain the overhead system in a predetermined fixed 30 relation in order to give the best operation of the buses.

The necessity for such fixed relation is due to the fact that the trolley heads supporting the current collectors, which engage the overhead system, are independent of each other and are adapted to pivot universally relative to the trolley bus and, therefore, the overhead system must be such that it in itself and the elements making up the system will properly guide the current collector while the bus is free to move laterally in either direction relative to the overhead system.

Such requirements and operation is not required in the case of so-called street car operation where the vehicle moves along a fixed track, 45 at least not to the same extent.

50 My invention herein described may be employed not only in the operation of trolley buses but also in combination with the operation of street cars, and in the latter case the negative wire is usually grounded at the source of power while the positive wire is located above the track on which the street car operates.

To attempt to connect the various overhead 55 switches, crossings, hangers, etc., by trolley wires

and maintain the elements in fixed relation, is not only very unsatisfactory from the operating standpoint but it is expensive to maintain the parts in a reasonably fixed relation, but by tying the switches, crossings, hangers, etc., together to form a substantially single, rigid unit, I am able to accomplish the results required.

My invention also includes electrically operated switches which may be controlled by the vehicle operator to either pass straight through or along 10 a main line or to take a branch line.

As the requirements to be met might be said to be almost legion, I prefer to make the various parts forming my invention so that they are more or less interchangeable, as for instance, various 15 types of electrically operated switches may be used to meet various requirements or the switches may be of hand operation, that is, operated by means of a rope alongside of the pole; the angle which the branch makes with respect to the main line may vary thus requiring different switch pans; the curvature of the turn-out may vary; the switch pans and other parts are required to take various sizes and styles of trolley wires and also the distance between the switches themselves 20 and between the switches and crossing may vary.

25 In the invention which I have shown in the drawing, there is disclosed two spaced electrically operated switches so arranged that they will operate with "power on" and "power off" and it 30 is usual in this particular type of switch to have the switch normally set to guide the current collector straight through the switch and "power off," that is, with the controller on the vehicle open, and in order to move the switch to the branch connection to guide the current collector onto the branch or turn-out wire the vehicle operator moves his controller to the "power on" 35 position as the collector crosses or passes through the switch. This setting, however, may be reversed.

40 In the embodiment disclosed, I employ electrically operated switches A and B provided with body or pan members 1 and tongues 2 and shown held in the straight through position by means of the springs 3. Each pan is provided with projecting arms 4, 5, and 6 by means of which the current collector is guided onto and off the pan. The switches A and B are held in spaced relation by means of insulators 7 and 8 and are also 45 provided with pull-off lugs 9 to which supporting and strain wires may be attached.

45 To operate the switch tongues to turn-out position, I employ an electrically operated mechanism C which comprises a coil 10 and a plunger 11, the 50

latter being mechanically connected to the switch tongues 2. One end of the coil 10 is electrically connected to the pan 1 and the other end is in electrical connection with the trolley wire as later explained.

The crossing D is provided with a pan 12 and arms 13, 14, 15 and 16 and is adapted to guide the current collector straight through the crossing either in connection with the main wire or with the branch wire.

The ends of the arms on both the switches A and B and the crossing D are provided with a U-shaped groove to receive the ends of fittings to be attached thereto as further described.

16 The operation of the switches A and B herein disclosed requires that such switches be insulated from the trolley wire excepting through the coil 10 and connection 17 thereto.

To effect such insulation, I have shown in Figs. 20 2 and 3 somewhat enlarged views of the parts to meet such requirement. The end of the frog is shown partially, and connected to the frog arm 6 is a live spacer 18 which has a tongue 19 at one end positioned in the groove of the arm 25 6 and held in place by the bolts 20. The spacer 18 has a U-shaped groove 21 at the other end to receive the control insulator 22.

The control insulator comprises an elongated bar 23 having one end positioned in the groove 30 21 and insulated therefrom as shown at 24. The insulation may comprise sheet insulation as a part of the member 18 or of the member 23. The control insulator and live spacer are held in position by means of bolts 25 which are insulated from one or both of the members 18 and 23 by bushing insulators.

The other end of the control insulator 22 is arranged to be inserted in the U-shape grooved end 26 of the trolley wire tip 27 which is adapted 40 to receive and hold the main trolley wire 28 in place by the screws 29.

The control insulator 22 is provided with detachable clips 30 and 31 with their inner ends adjacent but separated a small amount. The clip 31 is insulated from the member 23 but is electrically connected to the member 18 by means of the jumper 32 or other appropriate means. The clip 30 is electrically connected with the main trolley wire 28 as is evident. The member 23 is provided with the connecting lug 33 to receive conductors.

If the length of the pan will not give a sufficient length of time to energize the coil 10, then the length of the member 18 plus the length of the pan is made sufficient such that a trolley bus moving in the direction of the arrow in Fig. 1 will be assured of a sufficient time of contact of the collector in crossing the switch to energize the coil 10 and move the tongue 2 if the operator wishes to alter the position thereof. The members 18 are not necessary if the switches are sufficiently long in which case the ends of the bar 23 are placed in the grooves of the arms 6 in insulated relation thereto.

65 Any arcing which may occur as the current collector moves along the system described will take place between the clips 30 and 31 and these have been made relatively small, inexpensive and easily renewable when burned.

70 To further insulate the switches A and B from the trolley wire, the grooved ends of the arms 4 and 5 are provided with adapter members 34 which have tongues held in the groove of the arms by means of the bolts 35 and insulated from 75 the arms by means of the insulation 36.

The adapter 34 of the arm 4 has a groove at one end in which is positioned the tongue 37 of the trolley wire tip 38 in which is positioned the end of the main trolley wire 39. Means 35' are provided for securing the adapter and trolley wire tip together and also securing the trolley wire in position.

In order to forego breaking the continuity of the trolley wires 28 and 39, I provide a jumper 40 having its ends connected to the control insulator 22 and the adapter 34 respectively.

The arm 5 of switch A is joined with the arm 15 of the crossing D by means of the rigid spacer 41 which comprises preferably an angle or T bar of rolled steel having one leg 42 arranged to 15 guide the current collector along its lower edge and may be curved or used straight. The vertical leg 42 of the angle bar 41 is arranged to be connected to a grooved end on the arm 15 and to fit the clevis end of an adapter 34 which has the 20 tongue end positioned in the arm 5 in the manner shown in Figs. 4 and 5. The adapter 34 is insulated from the arm 5. It will be evident that the rigid spacer 41 will maintain its curvature due to the construction of the angle bar. 25

The rigid spacer 44 has one end connected to the arm 5 of the switch B by an adapter 34 in the same manner as the end of the spacer 41 is connected to the end of the arm 5 of the switch A.

The other end of the spacer 44 is provided with 30 a tongue 45 to which is secured the trolley wire tip 46 held in place by the bolts 47 and which receives and holds the end of the branch trolley wire 48. The latter described end of the spacer 44 is held in position relative to the crossing D 35 by means of the insulated member 49 which is connected to a transverse bar 50 which is preferably welded to the spacer 44.

The general construction of the spacer 44 is the same as that of spacer 41 and while not 40 necessary, I prefer to curve the spacers which gives smoother and more reliable operation of the current collector.

The end of the arm 4 of the switch B is connected to the arm 13 of the crossing D by means 45 of a spacer 51 which has an insulated portion 51' with one end positioned in the groove of the arm 13 and the other end positioned in the groove of a metal portion 52. I construct the spacer portion 52 of a rolled steel bar, the lower edge 50 of which is adapted to guide a current collector.

The other end of the metal spacer portion 52 is connected to the grooved end of the arm 4 of the switch B by means of an adapter 34 in the same manner as the spacer 41 and 44 are connected to the arms 5. 55

I place around the switch B a jumper 53 which is connected to the control insulator and the adapter respectively thus the spacer portion 52 is energized of the same polarity as the main 60 trolley wire 28' thereby permitting operation of the vehicle if it should come to rest with a current collector on the member 52.

The arm 16 is provided with a trolley wire tip 54 to receive and hold the branch trolley wire 65 end 55 in electrically connected relation to the crossing D.

To the clevis end of the arm 14 of the crossing D, I secure another insulator 56 and to the other end of the insulator 56 is attached a trolley wire 70 tip 57 to receive and hold the main trolley wire end 58. The insulators 51' and 56 are sufficient to insulate to the full potential used and keep the polarities safely separated.

In order to maintain proper spacing between 75

the trolley wire 39 and the crossing D, I use an insulator 59 which has one end 60 adjustably secured to the crossing D and the other end to a hanger 61 which is attached to the trolley wire

5 39. Span wires 62 and 63 are connected to supports which assist in suspending the parts and maintaining them in relative longitudinal position.

10 The lower surface of practically all of the parts which I have described are in alignment and for the purpose of smoothly conducting the current collector across the device which I have described.

15 With the construction which I have described, the switches A and B or other types of electrically operated switches and the crossing D are held in practically fixed relation.

20 It will be noted by the positive and negative signs and the various insulations that the two polarities are thoroughly insulated from each other, and if street cars are operating over the system, as for instance, over the positive wire and if the switch A is set to the straight through position and it is desired the car shall take the curve, the operator will set his controller to 25 "power on" position before crossing the spacer 22 and the switch A which is the same procedure as carried out by the bus operator under like circumstances.

30 In order to protect the coils 10 from a continual flow of current if the vehicles should stop with the current collector on the spacers 41 and 44 or on 35 51 and the wire 39, I place the insulation necessary to maintain the separation of the polarities, at or adjacent the ends of the frogs. 35 The accessories on a street car or bus may at times draw a large volume of current and this would pass through the coils 10 if proper insulating precautions were not used.

40 A jumper 64 connects the two adapters 34 on each switch A and B.

45 By making the ends of the parts with grooves and tongues and maintaining a standard throughout the line of parts, I am able to combine the various parts to meet varying requirements without unduly multiplying the parts required.

As there are many modifications to which my invention is subject and which my disclosure will suggest to those skilled in the art, I wish to be limited only by my claims.

5 I claim:

1. A control device forming part of an overhead trolley wire device comprising an elongated flat bar of metal, insulating means positioned longitudinally along the side faces of the bar adjacent one end thereof, openings transversely disposed to the longitudinal axis of the bar at one end of the bar to secure to the end of the bar another part of the overhead device, the openings at the insulated end provided with insulating bushings, a pair of renewable clips attached to the bar to guide a current collector, one clip in electrical contact with the bar and the other clip adjacent the insulated end of the bar and insulated therefrom by the aforesaid insulating means, the adjacent ends of the clips being so constructed and spaced that a passing current collector will be in engagement with both clips at the same time and means electrically connected to the other end of the metal bar and having means to receive and hold a trolley wire.

2. A control device forming part of an overhead trolley wire device comprising an elongated bar of metal, insulating means positioned along the sides of one end of the bar, transverse openings through the bar and insulating means to receive means to secure the bar to another part of the trolley wire device, insulation interposed between the bar and the last said means to insure the insulation of the said means and said another part from the bar, means attached to the other end of the bar in direct electrical connection therewith, a renewable clip electrically connected to the bar adjacent the last said means and a renewable clip attached to the bar adjacent the other end of the bar and insulated from the bar, the adjacent ends of the clips being so arranged that a current collector passing across the device will at some period engage both clips.

SAMUEL S. MATTHES. 45
